Primary Examiner — Bridget L Eland*(74) Attorney, Agent, or Firm* — Gerald P. Joyce, III(57) **CLAIM**

The ornamental design for a wireless identity transceiver, as shown and described.

DESCRIPTION

FIG. 1 is a front/right side perspective view of the wireless identity transceiver design.

FIG. 2 is a front view of the wireless identity transceiver design.

FIG. 3 is a back view of the wireless identity transceiver design.

FIG. 4 is a left side view of the wireless identity transceiver design.

FIG. 5 is a right side view of the wireless identity transceiver design.

FIG. 6 is a top view of the wireless identity transceiver design; and,

FIG. 7 is a bottom view of the wireless identity transceiver design.

The broken lines shown in FIGS. 1-7 represent portions of the wireless identity transceiver that form no part of the claim.

1 Claim, 7 Drawing Sheets(56)
